(57) **CLAIM**

An ornamental design for set of drag reducing panels for a road tractor, as shown and described.

DESCRIPTION

FIG. 1 is a perspective view of the set of drag reducing panels for a road tractor;

FIG. 2 is an enlarged view of a portion of FIG. 1, to more clearly illustrate the set of drag reducing panel thickness and holes punched there through;

FIG. 3 is a side view of the design of FIG. 1;

FIG. 4 is a front view of the design of FIG. 1; and,

FIG. 5 is a top view of the design of the set of drag reducing panels for a road tractor.

The broken line showing of a road tractor is included for the purpose of illustrating the set of drag reducing panels and forms no part of the claimed design.

The appearance of the of the drag reducing panel's hole pattern and thickness as depicted in FIG. 2 is representative of the appearance that extends across the entirety of the claimed design.
